(57) **CLAIM**

I claim the design for an irrigation holder, as shown and described.

DESCRIPTION

FIG. 1 is a top, right perspective view of my design;

FIG. 2 is a top view of my design;

FIG. 3 is a bottom view of my design;

FIG. 4 is a front view of my design;

FIG. 5 is a rear view of my design;

FIG. 6 is a right side view of my design;

FIG. 7 is a left side view of my design;

FIG. 8 is a bottom perspective view of my design; and,

FIG. 9 is an enlargement of the indicated area of detail of FIG. 8.

Elements in the figures shown in dash-dash lines represent portions of an irrigation holder and form no part of the claimed design.
